DUPLICATOR

Julius H. Hauf, Chicago, Ill.

Application August 5, 1932, Serial No. 627,578

18 Claims. (Cl. 101—133)

This invention relates in general to a duplicating machine of the gelatine duplicator type and has more particular reference to an improved, compact, simple carriage type machine of this class.

Among the objects of the invention are to provide a slidable type of paper carriage; to provide an improved gelatine duplicator clamp; to provide means to engage the side edges of the duplicator copying sheet; to provide a carriage paper stop; to automatically apply and lift the paper sheeting roll as the carriage is moved over the platen; to provide improved adjustable paper guides; to make a folding carriage for reducing the height of the duplicator to fold more compactly; to make a simple, light, inexpensive duplicating machine of sheet metal; to make an improved duplicator sheet adapted to be clamped at the ends and gripped at the sides for holding it tightly in place; and in general to produce the machine herein shown and described.

Other objects of the invention will appear hereinafter, the preferred embodiments being illustrated in the accompanying drawings.

In the drawings, Fig. 1 is a side elevation and Fig. 2 is a plan view of a duplicator constructed in accordance with the principles of this invention;

Fig. 3 is a section taken on the line 3—3 of Fig. 2;

Fig. 3a is a detail section showing the roller in rest position;

Fig. 4 is a view of the carriage in open or unfolded position;

Fig. 5 is a transverse section of the machine through the carriage;

Fig. 6 is a top view of a simplified form of carriage;

Fig. 7 is a section taken on the line 7—7 of Fig. 6;

Fig. 8 is a section taken on the line 8—8 of Fig. 7;

Fig. 9 illustrates a form of the invention in which the duplicator sheet is mounted on rolls below the platen;

Fig. 10 is a sectional view of a paper guide;

Fig. 11 is a detail section of one end of an improved duplicator sheet; and

Fig. 12 is a fragmentary corner of a duplicator sheet having a side space for the engagement of lateral holding clamps.

In duplicating machines of this type the means for attaching and holding the gelatine film is an important feature. In the present construction the gelatine copying film is simultaneously

clamped at both ends of the base plate and may also be engaged at the sides for holding it firmly in place. A carriage having an adjustable paper guide is movable in slides at the sides of the base and includes a platen which presses the paper with uniform pressure against the gelatine film and is automatically lifted as soon as the applying pressure is released, thus preventing the platen roller from forming a groove in the film and also preventing the roller from receiving an impression from the film.

Referring now more particularly to the drawings, a supporting base designated generally with the numeral 1 is preferably formed of sheet metal with depending sides 2 having bottom corner supports 3 preferably of rubber and of a vacuum cup type. A top base plate 4 has angular reinforcements 5 at the under side for strengthening and stiffening it but still leaving a considerable space within the base 1 for storing paper, carbons, duplicating films, and other articles and supplies.

A clamping frame comprising channeled side guide rails 6 and end cross pieces 7 and 8 is pivotally connected to the base 1 at one end thereof by means of plates 9 secured to the frame and pivots 10 extending therethrough into the base. The cross piece 7 at one end has a reversely bent portion 11 with slots 12 therein at intervals forming clamping tongues 13, the upper extremities of which are bent inwardly toward the base 1 with a strip or blocks 14 of resilient material such as sponge rubber or the like, placed back of the tongues for forcing them yieldingly and in addition to their own resilience in the direction of the base 1. The cross piece 8 at the other end of the clamping frame is also provided with a reversely bent resilient portion 15 having similar clamping tongues 16 and with resilient material 17 forcing them in the direction of the base.

At the sides of the base 1 and overlapping the edges thereof are spring tongues 18 secured to or formed as a continuation of the guide rails 6, as shown more clearly in Fig. 5. These clamping fingers 18 and the clamping tongues 13 and 16 at the ends of the frame are moved into engagement with a gelatine copying film 20 which is placed upon the base 4 and has extremities which are inserted between the ends of the base and the clamping fingers 13 and 16 when the clamping frame is raised to the broken line position in Fig. 1.

The copying film 20 has a copying composition of gelatine and glue 21 applied to a sheet of fabric 22 preferably of tough paper, cloth and the like, and in the form shown more particularly by

Figs. 11 and 12, the ends 23 and the sides 24 are turned over upon themselves and connected by stitching 25 to strengthen and reinforce the film. This also provides additional means for the engagement of the clamping tongues 13 and 16 at the ends of the film 20 and for the holding fingers 18 at the sides of the film.

In order to hold the clamping frame in film locking position a pair of ears 26 are secured 10 to the frame at its free end, each having a perforation 27 adapted to be engaged by a locking projection 28 mounted on a spring 29 secured to the inside of the base 1 and extending through an opening 30 in the wall thereof which registers 15 with the perforation 27 as the clamping frame is pressed into locking engagement with the film 20. To release the frame these projections 28 are pressed inwardly and the free end of the frame is raised, the ears 26 ride over the rounded ends 20 of the projections 28 which spring back through the openings 30 for reengagement with the clamping frame.

Slidable upon the guide rails 6 is a carriage comprising side plates 31 each having a channel portion 32 engaging in the channel of the guide rail 6 and connected over the top of the base by cross pieces 33, and a hinged carriage member comprising opposite side plates 33 hinged to the other carriage plates 31 by pivots 34 and connected together from the top of the plates 33 by a cross piece 35, the intermediate portion of which forms a handle 36. Extending transversely of the upper carriage member and secured to the end plates 33 thereof is a paper table 37 having an angularly down-turned rear edge 38 with slots 39 adjacent the top for receiving paper guides 40.

Also mounted in the upper carriage member and extending transversely thereof is a roller platen 41 preferably made with an outer cover 42 of resilient material such as rubber and having an interior metal shell or rod 43 pivoted at its ends in plates 44 which are hinged as shown in Fig. 3 upon pivots 45 at one end of each plate, the other free end of the plate 44 being pressed toward the inclined paper table 37 by a spring 46 which extends around the pivot 45 and over the plate 44, the paper table 37 constituting an engagement for the free end of both pivoting plates 44 and limiting the movement of the roller of the roller platen 41 in the direction of the copying film.

In order to hold the carriage parts in proper position with respect to each other, the lower carriage member has a number of springs 47 attached at one end to the under side of one of the cross pieces 32 with a free end or projection 48 engaging a fixed portion of the upper carriage member such as the paper table 37 and tending 55 to raise the upper carriage member except when pressure is applied thereto in feeding the paper. To limit this movement, the lower carriage member has its side plates 31 each provided with a perforation 49 and the side plates 33 of the upper carriage member are provided with corresponding slots 50 into which extends a projection 51 carried by a spring 52 attached at its end to the inside of the plate 31 and the projection 51 adapted to be depressed to disengage the projection 50 from the slot 50 when it is desired to rotate the upper carriage member upon its pivots 34 to the position as shown in Fig. 4. In normal operation, however, the springs 47 tend to raise the upper carriage member with respect to the sliding carriage thereby raising the platen 41 from a posi-

tion to engage the copying film 20 except when the upper carriage member is positively applied for that purpose. With this construction the upper carriage member may be pressed upwardly by the springs 47 to the limit of movement permitted by the slots 50 which will keep the platen from contact with the copying film except when it is positively applied thereto.

In its starting or at rest position at one end of the base 1 the platen 41 is raised with the upper carriage member above the level of the copying film 20 and preferably rests upon an angled extension 53 of the cross piece 8 of the clamping frame as shown in Fig. 3a which also constitutes a stop for the insertion of a sheet of paper 54 inserted in the carriage. Intermediate the ends 10 of this extension 53 is a cut-out or depression 55 at which the edge of the paper may be engaged by the fingers of an operator for engaging and withdrawing it from the copying film at this end 15 after the carriage has been moved away from this end of the paper.

It will be understood that in operating this construction a piece of paper 54 is inserted in the carriage under the platen and against the extension 53 with the platen 41 resting on the extension. The forward movement of the carriage first moves the platen off of the extension on to the paper, pressing the paper against the copying film until the desired length of paper has been applied 30 to the copying film. If the end of the paper is retained in the carriage a reverse movement of the carriage will raise or pull the paper from the copying film 20 and by holding the free end of the paper against the paper table, the paper 35 may be withdrawn without the curling effect which is so objectionable in some machines. If the carriage has passed entirely over the paper, the starting end of the paper may be raised by engaging it through the depression 55 and pulling 40 it off of the film from this end.

A suitable paper guide 40 for positioning the paper in the carriage comprises a channel shaped strip 57 having a spring metal clip attached to one end thereof and the other end embracing 45 the opposite sides of the paper table 37, the clip being folded upon itself and insertable through the slot 39 at the upper edge of the paper table and having a notch 59 for engaging the inclined edge 38 of the paper table for holding the guide 50 in proper position with respect to the slot. This guide is freely adjustable along the slots 39 by simply pinching the two upper edges of the clip together, thereby releasing it from engagement with the paper table and by making the guide 55 member 57 in channel form, the same guide may be used for opposite sides of the carriage.

Instead of a movable two piece carriage a 60 slideable single piece carriage may be used, as shown for example by Figs. 6, 7 and 8, in which the side pieces 60 are formed at their lower ends with a channel shaped section 61 to engage the guide rails 6 and they are connected over the top by a fixed handle 62. A roller platen 63 is mounted in arms 64 pivoted eccentrically 65 to the side pieces 60 by pivots 65 and pressed in film engaging position by springs 66. A fixed paper table 67 is secured to the end pieces at one side of the platen 63 and engages the free end of the arm 64 to limit the movement of 70 the platen in the direction edged by the spring 66. The arms 64 are connected by a cross piece 68 with a downwardly turned portion adjacent the handle 62 so that in operating this carriage back and forth upon the base the fingers or 75

hand of the operator are moved against the cross piece 68 in one direction of movement to raise the platen 63 from its contact with the copying film against the tension of its springs 66. When moved in the other direction the cross piece 68 is not engaged thereby, allowing the platen to press the paper 54 against the copying film as desired.

Instead of having a copying film of a size to fit the base plate only, a continuous film 70 may be provided as shown in Fig. 9, mounted upon rollers 71 at the underside of a base 72 and having a hinged clamping frame 73 for engaging the film at the sides and ends as above described. Either a double or a single type of carriage may be used with this structure as set forth above.

One of the principal objects in making the carriage in two parts is to rotate the upper member with respect to the other one particularly as shown in Fig. 4, so that the entire duplicator may be packed more compactly and fit more flatly in a carton or in a drawer. Sheet metal is used throughout wherever practical to make the construction light and strong and it is intended that where necessary the parts be secured together by spot welding which simplifies the construction and fabrication of the parts.

I claim:

- 30 1. A duplicator comprising a film holding base and means comprising a frame pivoted at the sides below the top of one end of the base and applied over both ends of the base for clamping opposite ends of the film.
- 35 2. In a duplicator, a film holding base, clamping means comprising a single frame extending over both ends of the base and pivoted thereto and movable simultaneously to engage and clamp opposite ends of the film.
- 40 3. In a duplicator, a film holding base, a clamping frame for the film extending over opposite ends of the base, pivoted to the base at one end and movable into engagement with the ends of a film to clamp both of them against the base.
- 45 4. In a duplicator, a film holding base and clamping means therefor comprising a frame extending about the base having resilient fingers extending over the opposite edges of the base and movable into engagement with the edges of a duplicator film lying thereon.
- 50 5. In a duplicator, a film holding base, clamping means therefor comprising a frame extending about the base and movable downwardly over the ends of the film to clamp them between the frame and the base, and yielding fingers also carried by the frame adapted to engage the film at the sides thereof for additionally holding it in place.
- 55 6. In a duplicator, a film holding base, a duplicator film extending over the base and overlapping it at the ends, and a clamping frame applied over opposite ends of the base and having yielding means at the ends of the frame for resiliently clamping the ends of the film between the frame and the base.
- 60 7. In a duplicator, a pair of side guide rails and a carriage slidable along the guide rails, the carriage having a part rotatable beyond the end of the guide rails for folding it more compactly.
- 70 8. In a duplicator, a base, a copying film applied thereto, clamping means comprising a frame extending over opposite ends of the base, pivoted to the base and engageable with the film to hold it on the base, and releasable means

for holding the clamping frame with respect to the base.

9. In a duplicator, a film supporting base, a clamping frame for the film surrounding the base and pivoted thereto, the frame comprising side guide rails and end cross pieces and resilient means extending from the cross pieces for clamping the film in place, and paper holding means slidable along the side guide rails for applying sheets to the film.

10. In a duplicator, a base, a copy film resting thereon, means in connection with the base for clamping the film thereon, said means comprising side guide rails, a carriage slidable along the guide rails, a rotatable platen and means for mounting the platen in the carriage to move it toward and from the film in applying sheets thereto and withdrawing them therefrom.

11. In a duplicator, a film holding base, means for clamping a film to the base, guide rails, a two part carriage slidable upon the guide rails having a hinged member movable relatively to the other part, a platen carried by the said hinged member and spring means between the carriage parts for raising the platen carrying part from the sliding part.

12. In a duplicator, a film supporting base, means for clamping the film on the base, guide rails at the sides of the base, a paper carriage having a part slidable on the rails, a platen carrying part hinged thereto, means tending to press the platen against the film, and spring means tending to raise the platen carrying part from the other part.

13. In a duplicator, a base member and a copying film thereon, guide rails at the side of the member, a paper carriage having a part slidable on the rails, a platen carrier hinged thereto, spring means tending to raise the platen carrier from the slidable carriage, and means forming a releasable connection for limiting the normal raising movement and for overturning the platen carrier at one end of the slidable carriage.

14. In a duplicator, a film supporting base, a carriage movable on the base, a paper platen hinged in the carriage, a spring tending to raise the platen in the carriage, and means including a handle for applying the platen to the film in one direction of movement of the carriage and the spring automatically raising the platen from engaging the film in moving the carriage by the handle in the other direction of movement.

15. In a duplicator, a film supporting base, a carriage movable in the base, a paper platen hinged in the carriage and means including a handle for applying the platen to the film in one direction of movement of the carriage and for automatically raising the platen from engaging the film in the other direction of movement of the carriage, the platen mounting including a cross-piece adjacent the handle adapted to be manually engaged for raising the platen in one direction of movement of the carriage.

16. In a duplicator, a paper carriage including a platen, a paper table inclined thereto having a downwardly turned rear edge with a slot in the upper edge, and a paper guide comprising a member overlying the table to engage paper at either side thereof and a V-shaped spring clip secured to the back of the guide and insertable in the slot with a notch in one side of the clip to engage the edge of the slot and hold the guide in place.

17. In a duplicator, a film supporting base, a carriage slidable along the base, means forming a fixed raised rest at one end of the base, a paper

platens movably mounted in the carriage, and adapted to be supported on the rest at the end of its movement, the rest limiting the position of the end of a sheet to be printed when it is inserted in the carriage under the platen, and means to press the platen against the film when the carriage moves it from said rest.

18. In a duplicator, a structure in accordance with claim 17 in which the rest has an intermediate recess wherein the edge of a sheet to be printed may be manually engaged after the carriage is moved away for raising a sheet by this edge.

JULIUS H. HAUF.
